United States Patent Office

Des. 224,172
Patented July 4, 1972

224,172

DIALYZING UNIT

Clarence E. Schmidt, Santa Ana, Calif. (10510 Chapman Ave., Suite 12, Garden Grove, Calif. 92640)

Filed May 13, 1970, Ser. No. 22,962

Term of patent 14 years

Int. Cl. D24—02

U.S. Cl. D83—1

FIG. 1 is an isometric view of a dialyzing unit showing my new design;

FIG. 2 is a view in front elevation of the unit of FIG. 1;

FIG. 3 is a top plan view of the unit of FIG. 1; and
FIG. 4 is a view in rear elevation of the unit of FIG. 1.

I claim:

The ornamental design for a dialyzing unit, substantially as shown.
